UNITED STATES PATENT OFFICE.

EPIFANIO V. N. TOMASULO, OF CINCINNATI, OHIO.

WINDOW-SHADE GUARD.

1,379,664.

Specification of Letters Patent.

Patented May 31, 1921.

Application filed February 19, 1920. Serial No. 359,789.

To all whom it may concern:

Be it known that I, EPIFANIO V. N. TOMASULO, a subject of the King of Italy, residing at Cincinnati, in the county of Hamilton and State of Ohio, have invented certain new and useful Improvements in Window-Shade Guards, of which the following is a specification.

My invention relates to window-shades and the like, and the objects of my improvements are to prevent the edges of the shade from scraping against the shade-brackets at the ends of the shade roller, thereby avoiding wrinkling, tearing and raveling of the shade material when the shade winds unevenly on the roller; and, preferably, to have the guarding element freely rotatable relatively to both the shade-roller and the shade-roller bracket, whereby the guarding element can partake as nearly as possible of the same lineal velocity as any portion of the shade edge frictionally contacting therewith at any stage of the winding or unwinding of the shade. Other objects will appear in the course of the ensuing description.

I attain these objects by the device illustrated, for example, in the accompanying drawing, in which—

Figure 1 is a perspective view of a shade equipped with my invention as I prefer to construct it;

Fig. 2 is an outside elevation of one of the guards;

Fig. 3 is a vertical section of the same on a plane corresponding to the line 3—3 of Fig. 2;

Fig. 4 is a perspective view corresponding to Fig. 2;

Fig. 5 is a similar view of the opposite side of the guard;

Fig. 6 is a vertical longitudinal section on a plane corresponding to the line 6—6 of Fig. 1, middle parts being omitted for lack of space, and the shade being represented as running up on the guard;

Fig. 7 is a similar section, but including the left end only, and showing a modification of the guard;

Fig. 8 is a section corresponding to Fig. 3, but showing another modification of the guard; and

Fig. 9 is a section corresponding to Fig. 7, showing another modification of the guard, and, associated therewith, a modified bracket.

My invention involves the use of the ordi-

nary well known shade-roller 1 and shade 2, having at the left end the detent stud 3 projecting from the spring motor mechanism mounted in the shade-roller as usual, but not herein shown, and at the other end the spindle 4. Any shade roller answering to this description may be used, and also, as shown in Figs. 1 to 7, the ordinary brackets 5 and 6 are used at the left and right ends, respectively, of the roller 1; the left-hand bracket 5 having the slot 7 cut down from its top to the center of the forward part of the bracket, with the slight shoulder 8, to receive and hold non-rotatable the detent stud 3 of the roller, and the right-hand bracket 6 having the inwardly extending circular boss 9 with the central opening circular to receive the roller spindle 4 for free rotation, as usual. Such brackets are attached to the window frames or the like by means of their perforated bases 10 as shown in Fig. 1; or, under some conditions, are attached through holes 11 in the forward part of the bracket, as seen in the left-hand bracket in Fig. 1. There are variations of these brackets; and it will be understood that my invention is not limited to use with any particular bracket or shade-roller mechanism.

My improved guard, in its preferred form, as shown in Figs. 1 to 6, inclusive, is a sheet-metal cup 12 with its rim 13 radially extended all around, and with the annular flange 14 turned down from the outer edge 90 of the rim 13 all around, forming the periphery of the guard. The formation is thus described to make it more readily understood; in practice, such a cup is drawn into the described shape at a single operation. They are thus very economically manufactured.

In the center of what corresponds to the bottom of the cup 12, is the circular opening 15. The inner diameter of the cup 12 and the diameter of this opening 15 are preferably so relatively proportioned that the cup 12 will slip readily over the end of the shade-roller 1 and the opening 15 will receive loosely the detent-stud 3 or the spindle 4, accordingly as the guard is the one on the left-hand or the right-hand end of the roller; and preferably the opening 15 is large enough to allow the guard to bear partly on the shade-roller convex surface with the inner surface of the cup wall, and partly on the stud 3 or spindle 4, as the case may be,

with the edge of the opening 15. This holds the guard approximately coaxial with the shade-roller 1, but the looseness of its mounting permits it to rotate very freely, whether 5 it be on the angular stud 3 or the round spindle 4; and the partial resting on the shade-roller end part may cease upon operation of the device, as the guard is pushed to a more nearly coaxial relation to the shade-
10 roller.

With the two guards, alike at both ends of the roller, thus on the roller, the roller is mounted in its brackets 5 and 6 in the usual well known manner; the relatively thin cup-
15 bottom part of the guard readily lying loosely in the slight space always left between the shade-roller ends and the respective adjacent brackets 5 and 6, in correct mounting of window shades in the well known manner.
20

Preferably, the junction corner between the rim 13 and flange 14, at 16, is rounded to an ample radius; while the outer edge 17 of this flange 14 is discontinued short of the outer face plane of the cup-bottom part.
25 These provisions better insure the smooth working of the device; the first avoiding cutting of the shade if it climbs onto the guard, as in Fig. 6, and the second avoiding contact 30 of the raw edge 17 with the brackets 5 and 6 behind the roller 1.

In the modification of Fig. 7 the guard is the same as was just described, except that its rim 13' is turned down so as to present a convex surface inwardly toward the shade edge, and the flange 14' turned down from the outer edge of this convex rim 13' is correspondingly narrower. Such a formation may, under some conditions, better prevent 40 climbing of the shade onto the periphery of the guard.

In the example of Fig. 8, the guard is a hollow disk, with one circular face 12" having the small opening 15" in its center, like 45 the opening 15 of the other examples, and with its opposite circular face 13" having the larger circular opening 12^a substantially of the diameter of the cup interior in the preceding examples, and located centrally of the disk. The outer shell or peripheral part 14" joins the part 13" by an ample curve at the junction corner 16"; and joins the other part 12" through a curved junction corner 17" that may be of any desired radius, 50 so that this part of this guard may be smoother than the edge 17 of the preceding example, avoiding cutting of the shade if it runs extremely far over the guard. This latter occurrence is not frequent, however; 55 and this hollow-disk-shaped guard is more difficult to form of sheet metal than the open cup formation of Figs. 1 to 6, or of Fig. 7.

In Fig. 9 the bracket 5^b is similar to the ordinary bracket 5 of the preceding examples, but its outstanding part 18 is circular
60

and of about the diameter of the modified guard. This latter comprises the inner circular face part 19 and the peripheral part 20, joined by the corner part 16^b of ample radius, with the outer edge 17^b of this peripheral part 20 very close to and covered by the peripheral parts of the circular outstanding part 18 of the bracket 5^b. It also comprises a sleeve 21 that is slipped onto the shade roller with fingers 22 formed lengthwise thereof by slitting it, to grip the roller. The outer end part of the sleeve 21 has the annular bead 23 extending out all around, and the inner part 19 of the cup-shaped part of the guard has the central opening with the annular off-set 24 coming over the bead 23 and down between it and the annular flange 25 that is turned out at the outer end of the sleeve 21. This permits the cup-shaped part to rotate on the sleeve independently of the shade roller and of the bracket. It will be understood that the circular shape of the bracket 5^b is not essential, and this special bracket may be dispensed with and the ordinary bracket used with the guard just described. Also, it will be understood that the right-hand bracket may be special with the circular part like the bracket 5^b, or may be the ordinary right-hand bracket; and the guard at the right end will 95 be identical with the left-hand guard just described, and merely inversely positioned.
90

This bracket, with an extension to cover the open outer side of the cup-shaped guard element, is equally applicable to the preferred guards of Figs. 1 to 6, or to that of Fig. 7. But in none of the examples is it essential; the principal use being to afford a more finished appearance to the installation than where the hollow inside of the guard 105 element may be seen from the side of the window. Other guards or brackets with closed or covered outer sides are disclosed and claimed in my co-pending application, Serial No. 356,199, filed February 4, 1920, in 110 which the example of Fig. 9 was also originally disclosed and claimed.

In any of the examples, the smooth inner sides of the guard elements avoid wrinkling, tearing or raveling of the shade edges when the shade runs unevenly to the right or left in winding up under the action of the shade-roller mechanism, and in unwinding also, under some conditions. Even if the shade edges climb over these smooth inner sides, 120 they encounter the smooth rounded corners and the smooth peripheral surfaces, from which the shade edges quickly slide back into their proper paths between the two guards.
115

It will be understood that any of the guard elements may be flat as shown, or convex as shown in Fig. 7, on their inner sides next to the shade edges. This convexity 130 may be desirable under some conditions, but

I have found in practice that the flat inner faces serve practically as well as convex faces ordinarily; and especially is this so when the guard is allowed to freely rotate at 5 approximately the lineal velocity of the shade edge at any time the edge contacts with the flat inner face. The convex face facilitates return of the shade to its proper path, once the shade has for any reason ridden over the guard; but the flat face tends to prevent this riding over entirely. Free rotation of the guard relatively to the shade-roller as well as to the bracket is best for these purposes, because as the shade accumulates on the roller, the diameter becoming greater, the shade travels at a greater lineal velocity than any part of the shade to which the guard can be attached; so that when fixed to the shade the disproportion 10 between the shade and guard lineal velocities increases as the shade accumulates in the winding-up operation. With the guard free to rotate, either on the shade-roller proper, as in Fig. 9, or partially thereon and 15 partially on the detent-stud 3, spindle 4, or other means near the end of the roller, according to the design and construction thereof, or else wholly on this projection, the guard may increase its speed to approxi- 20 mately that of the shade edge contacting therewith at any stage of the rolling-up, and the disparity of velocity and consequent friction and disruptive influence of the guard on the shade edge are minimized. 25 In any case, whatever be the relation of the guard to the roller, the relatively broad periphery of the guard, without any sharp angles or edges presented directly to an over-running part of the shade, almost completely avoids the cutting and abrasive action that will occur with merely a thin guard or guide disk at or upon the end of the shade-roller, which thin disk will receive the over-running shade part on its com- 30 paratively sharp periphery and act as a cutter thereon. Such a cutting action with such a thin disk or guide is especially ag- 35 gravated if the guide or disk is not allowed to turn relatively to the shade-roller, because the cutting action is so much more 40 severe due to the increasing disparity between the shade and guide lineal velocities. 45 Numerous examples have been given of embodiments of my invention, all of which have been explicitly illustrated and de- 50 scribed, but further modifications may occur under different conditions, as with shade-rollers different from that herein used for example, or in different windows, or for other reasons, and therefore, while certain 55 constructional details are deemed preferable in connection with my invention, and I have shown and described these specifically in elucidating the construction and use of my invention, as is required, I do not wish to 60 be understood as being limited to such precise showing and description, but having thus fully described my invention, what I 65 claim as new and desire to secure by Letters Patent is: 70

1. In combination with a window-shade, its roller, and the roller bracket, a guard element mounted near an end of said roller, between said shade and said bracket, said guard element being normally free to rotate 75 relatively to said roller and said bracket.

2. In combination with a window-shade, its roller, and the roller bracket, a guard element mounted near an end of said roller, between said shade and said bracket, said 80 guard element being normally free to rotate relatively to said roller and said bracket and having a shade-edge-conserving periphery.

3. In combination with a window-shade, 85 its roller, and the roller bracket, a cup-shaped guard element mounted between the roller and bracket normally free for rotation relatively to the roller and bracket, and extending over the adjacent end of the roller 90 and presenting a shade-edge-conserving surface toward the shade edge, and having a shade-edge-conserving periphery.

EPIFANIO V. N. TOMASULO.
